RICHARD MONTGOMERY, OF NEW YORK, N. Y.

Letters Patent No. 85,262, dated December 22, 1868.

IMPROVEMENT IN MACHINES FOR CORRUGATING METAL.

The Schedule referred to in these Letters Patent and making part of the same.

To all whom it may concern:

Be it known that I, RICHARD MONTGOMERY, of the city, county, and State of New York, have invented a new and useful Improvement in Rolls for the Manufacture of Corrugated-Metal Beams; and I do hereby declare the following to be a full and exact description thereof, reference being had to the accompanying drawings, forming a part of this specification, in which—

Figure 1 represents a longitudinal central section of my improved rolls, and

Figure 2, a transverse section in the line $x-x$ of fig. 1. The nature of my invention consists in the combination of three superimposed, grooved, and flanged rolls, for the purpose of manufacturing thereby corrugated-metal beams directly from the pile or bloom, said rolls being so arranged and disposed, one upon the other, with reference to their grooves and flanges, as that the iron may be passed consecutively between the rolls, in opposite directions, thereby avoiding the loss of time and disadvantages attendant upon the use of the double rolls heretofore employed for this purpose, in which there are constant interruptions in the process of rolling, caused by the necessity of returning the bar, after each pass, to the front of the apparatus.

In the accompanying drawings—

A, B, and C represent the solid metallic rolls of my improved apparatus, having suitable journals at each end thereof, revolving in bearings formed in a strong frame, D, supporting the entire machine. Said rolls are geared together outside of the frame, so as to revolve in unison.

A series of parallel grooves, alternating with parallel elevations, is cut in the circumference of the central roll B, and counterpart grooves and elevations are cut or formed alternately in the upper roll A and lower roll C.

The first groove, a , in the series, is cut near one end of the roll B, of the full width of the beam to be manufactured. A similar groove, a' , is also cut opposite thereto, in the upper roll A, and the united depth of the two is such as that the square metal pile or bloom to be rolled, when passed through the aperture 1, left thereby between the rolls as they revolve in contact, will be somewhat lengthened, and shaped into a bar.

The bottoms of the grooves a and a' , in the upper and central rolls A and B, are slightly furrowed in an opposite manner, so that one shall be the counterpart of the other, as illustrated in the drawing, and produce a slight corrugation of the bar S, passed through the aperture, No. 1, between them.

A double groove, b , No. 2, is next cut on the central roll B, so as to leave between its channels a projecting flange. The space enclosed between the outer edges of the double groove equals the width of the bar to be rolled.

A counterpart recess, b' , of the same width, is cut in the opposite face of the lower roll C, with two flanges

therein, to correspond with the opposite channels of the double groove b , 2, in the roll B.

At the next point, No. 3, in the circumference of the roll B, double flanges, c , are formed to project into a counterpart double-grooved recess, c' , cut in the upper roll A, said recess being of the same width as the beam S, to be formed in passing through the aperture 3.

Following this arrangement of counterpart grooved and flanged spaces formed around the rolls, the series of forming-apertures obtained thereby between the rolls is completed by double grooves, d and d' , cut in the roll B, receiving double flanges d and d' on the roll C, alternating with a double flange, e , 5, on roll B, projecting between double grooves e' on the roll A.

The metal pile, extended into a slightly-furrowed or corrugated bar, in passing between the rolls A and B, through the aperture No. 1, left by the recesses a and a' , is yet more deeply furrowed on opposite sides, in alternate parallel elevations and depressions or corrugations, by being passed through the aperture No. 2, left between the rolls B and C by the grooves b and b' . It is still further reduced in thickness when passed through the furrowed or grooved and flanged aperture, No. 3, between the rolls A and B, at c , and to very nearly the thickness required in the finished beam in passing through the aperture No. 4, between the rolls B and C again, and its folds or corrugations are finally gradually shaped and straightened, and made parallel and uniform, by passing it thereafter successively between the rolls A and B, and B and C, through the apertures or spaces 5 and 6, as indicated in the drawings.

The intervals m and m' , between the series of grooves and flanges a , b , c , &c., at the points 1, 2, 3, 4, &c., on the central roll B, are deeply grooved circumferentially, with recesses having an angular section, and corresponding angular flanges, m and m' , projecting both from the upper and lower rolls A and C, fit into and engage closely therewith, preventing longitudinal displacement or movement of the rolls A, B, C, and intimately combining them.

In using this combination of triple rolls A, B, and C, wherein the upper and lower rolls A and C alternately present counterpart forming-spaces coincidently with those formed consecutively upon the central roll B, the pile of metal passed through from one side, between the rolls A and B, at 1, (in the direction indicated by the arrows at y , fig. 2,) and thereby partially rolled, is immediately returned, between the rolls B and C, at 2, fig. 1, (in the direction indicated by the arrows at z , fig. 2,) which continues the reduction and formation of the bar as desired, and then again passed to the other side, between the rolls A and B, at 3, to be again returned, between B and C, at 4, passed back, between A and B, at 5, and finally returned, between B and C, at 6, in its finished form, each successive pass from 1 to 6 causing it to approximate more closely, in size and shape, to the finished bar, delivered from between the rolls B and C, at 6.

The series of forming-apertures 1 to 6, between the rolls, may be diminished or increased in number, as a smaller, thinner bar requires fewer passes, and a thick, heavy bar more passes, than the number herein enumerated.

By returning the heated-bar S from side to side, between the rolls, without delay, as herein set forth, its conversion into a corrugated beam is effected in about one-half of the time required with the old forms of apparatus, containing two rolls only. Hence, longer bars may be rolled in the same time, or, as the bar may be finished in so much less time, and can be, consequently, entirely formed and finished at a much higher degree of heat, cheaper iron may be used, or thinner bars manufactured. It is evident, also, that with my triple rolls a much more perfect and intimate weld and union of the metallic particles will be produced in the beam,

from the fact that the bar is rolled and finished into its final form, not only at one heat, but before it can have cooled to any very considerable degree.

Having thus fully described my invention,

I claim as new, and desire to secure by Letters Patent—

In a rolling-mill, consisting of three high rolls, arranged in the same vertical plane, and used for corrugating metal by passing it through a series of gradually-diminishing grooves alternately above and below the centre roll, the construction of the grooves as and for the purpose specified.

R. MONTGOMERY.
